UNITED STATES PATENT OFFICE.

NORMAN C. SMITH, OF WATERLOO, IOWA.

FIFTH-WHEEL.

SPECIFICATION forming part of Letters Patent No. 655,836, dated August 14, 1900.

Application filed June 2, 1900. Serial No. 18,876. (No model.)

To all whom it may concern:

Be it known that I, NORMAN C. SMITH, a citizen of the United States, residing at Waterloo, in the county of Black Hawk and State of Iowa, 5 have invented a new and useful Fifth-Wheel, of which the following is a specification.

My invention relates to fifth-wheels for vehicles; and the object is to provide an inexpensive fifth-wheel which will effectually prevent jarring of the king-bolt and evenly support the wagon-body, and thereby prevent the strain and distortion of the gear ordinarily produced by the uneven loading of the vehicle. Ordinarily in devices of this character 15 one of the elements of the wheel is of circular form, while the engaging element is simply provided with a substantially-inverted T-shaped opening for the circular element or disk, as this arrangement provides for the 20 ready separation of the parts when the king-bolt is drawn without necessity for the complete disassociation of the fifth-wheel. Where both elements of the wheel are made in circular form the interfitting annular flange is 25 bolted or otherwise detachably secured upon one of the members or the members are otherwise given a sectional character in order to facilitate the disassociation of the elements of the wheel. These various forms of fifth- 30 wheels either present insufficient bearing-surfaces or the assembling of their elements entails the attachment of a large number of loose parts, which is not only expensive but laborious.

35 The object of my invention is to produce a fifth-wheel having a maximum area of bearing-surfaces, the members being of novel form and one of them composed of a single casting and the other of a pair of semicircular 40 sections defined by a joint extending transverse to the bolster or axle, as the case may be, to which the sections are bolted and which serve to retain them against such relative movement as would effect their displacement.

45 To the accomplishment of the objects stated and others subordinate thereto, as will hereinafter more fully appear, the preferred embodiment of the invention consists in the construction and arrangement hereinafter fully 50 described, illustrated in the accompanying drawings, and embraced within the scope of the appended claims.

In said drawings, Figure 1 is a sectional elevation of the head-block and axle of a vehicle, illustrating the application of my fifth-wheel thereto. Fig. 2 is a perspective view of the fifth-wheel detached, and Fig. 3 is a perspective view of the subject-matter of Fig. 2 with one of the sections of the upper disk removed.

Referring to the numerals of reference employed to designate corresponding parts throughout the several views, 1 indicates the front axle of the vehicle, upon opposite sides of which are bolted a pair of depending parallel bed-plate flanges 2, cast integral with a circular bed-plate 3, formed with diametrically-opposite peripheral bolt-lugs 4, retained upon the upper face of the axle by bolts 5. From the upper face of the bed-plate 3 and 60 arranged concentrically thereon extends a circular bed-block 6 of considerably-smaller diameter than the disk 3 and surmounted by a circular head-disk or table 7 of greater diameter than the block 6, but of somewhat 65 smaller diameter than the disk 3, to constitute the periphery of the head-disk, an extended annular flange overhanging the annular bearing-face 8, defined upon the upper face of the disk 3 between the periphery of 70 said disk and the peripheral face of the bed-block 6. The flanges 2, disk 3, block 6, and head-disk 7 are all cast integral and constitute one element of the fifth-wheel rigidly retained upon the axle, as stated, by means 75 of the bolts 5, passing through the lugs 4, and by bolts 9, passing transversely through the axle and the flanges 2. The casting thus constructed is pierced axially by an opening 10, through which the king-bolt 11 is designed to pass. Above the axle is disposed, as usual, the head-block or front bolster 12, upon the opposite sides of which are disposed and secured by bolts 13 a pair of parallel 80 standing bolt-flanges 14, cast with the upper 85 member or bearing-disk 15 of the fifth-wheel. The disk 15 lies flat upon the upper face of the head-disk 7 and is of like diameter with the bed-disk 3, so that its edge projects beyond the edge of the disk 7 for the accommodation of a downwardly-disposed bearing-ring 16, fitting against the periphery of the disk 7, and the lower edge of which is inturned to form an inturned annular bearing- 90 95 100

flange 17 of a width corresponding to the width of the bearing-face 8 of the disk 3 and having a bearing upon the disk against the periphery of the bed-block and upon the under face of the head-disk 7, it being understood that the bearing-disk 15, ring 16, and inturned flange 17 are cast integral and that the disk 15 is provided with an axial opening 18 for the passage of the king-bolt, which, as premised, pierces both elements of the wheel axially and extends through the front bolster and axle, respectively.

It has been stated that one of the primary objects of the invention is to secure a maximum area of bearing-surfaces in a fifth-wheel of extraordinary simplicity. The vast area of bearing-surfaces is secured by the construction specified; but it will appear that provision must be made for assembling the elements thus constructed. This is done by forming the upper element or wheel member in a pair of semicylindrical sections, the straight diametrical edges of the sections defining the joint between said sections being disposed at right angles or transverse to the bolster, and therefore as a matter of course to the flanges 14, the purpose of this peculiar relation of the joint being to eliminate the possibility of relative movement of the sections under the torsional strain to which devices of this character are constantly subjected. Bolt-lugs 19, similar to the lugs 4, are provided upon the sections of the bearing-disk 15 to facilitate the attachment of said disk to the bolster.

It will now appear that when the fifth-wheel is assembled, as illustrated in Fig. 1 of the drawings, an extended bearing will be provided by the contact between the opposed faces of the disks 15 and 17 of the ring 16 and the periphery of the disk 17 and by the contact of the inturned flange 17 with the opposed faces of the disks 3 and 7 and with the periphery of the bed-block 6. It will also appear that the semicircular sections of the upper wheel member will be rigidly retained in juxtaposition by the bolster secured thereon at right angles to the joint and that the device may be quickly disassociated by removing the securing-bolts of one of the sections of the upper wheel member and by sliding said section out of engagement with the lower wheel member, which may then be readily withdrawn from the other section of the upper member without necessitating its detachment from the bolster. Attention is called, further, to the fact that by the provision of the parallel bolt-flanges and the bolt-lugs extending in planes at right angles to them each wheel member is firmly attached to the axle or bolster, as the case may be, by bolts passing through said elements both vertically and horizontally. I desire it to be understood, however, that while the embodiment of my invention illustrated and described is considered preferable at this time I wish to reserve

the right to effect such structural modifications and variations as may be embraced within the scope of the appended claims.

What I claim is—

1. A fifth-wheel composed of a non-sectional or single-piece member comprising a bed-disk, parallel bolt-flanges extending from one face of the disk, a circular bed-block of smaller diameter than the disk and extending from the opposite face thereof, and a head-disk surmounting the bed-block and having its edges extending beyond said block, and a second member composed of two semicylindrical sections which, when retained in effective relation with each other and with the first-named member, comprises a bearing-disk having a bearing upon the head-disk, a bearing-ring depending from the bearing-disk and bearing against the periphery of the head-disk, and an inturned horizontal bearing-flange below the bearing-ring and bearing against the opposed faces of the bed-disk and head-disk and against the periphery of the bed-block, and a pair of parallel bolt-flanges extending from the face of the bearing-disk opposite the head-disk, said flanges being disposed at right angles to the joint between the sections of the second wheel member.

2. A fifth-wheel comprising a lower member cast in a single piece and comprising a horizontal bed-disk, a horizontal head-disk of somewhat-smaller diameter, and an intermediate circular bed-block of smaller diameter than the head-disk, the bed-disk being provided with diametrically-opposed bolt-lugs extending from its periphery and with a pair of depending parallel bolt-flanges located at opposite sides of the bolt-lugs and extending entirely across the disk, and an upper wheel member composed of two identical semicylindrical sections each section being composed of a semicylindrical bearing-disk section, a depending semicircular bearing-ring section, a horizontal semicircular bearing-flange, and a pair of upstanding bolt-flanges disposed at right angles to the straight diametrical edge of the section, each bearing-disk section being provided with a peripheral bolt-flange located in a plane intermediate of, and at right angles to, the upstanding bolt-flanges, and said wheel members being provided with axial openings for the reception of a king-bolt.

3. A fifth-wheel comprising a pair of interfitting, circular members, one of said members being composed of two sections and having means for attaching the sections to the support with the joint between the sections disposed in a direction transverse to said support.

In testimony that I claim the foregoing as my own I have hereto affixed my signature in the presence of two witnesses.
